DESIGN FOR A LIGHTING FIXTURE FOR ELECTRIC LAMPS

Gustave W. Borkland, Chicago, Ill.

Application October 17, 1941, Serial No. 103,795

Term of patent 14 years

To all whom it may concern:

Be it known that I, Gustave W. Borkland, a citizen of the United States, residing at Chicago, in the county of Cook and State of Illinois, have invented a new, original, and ornamental Design for a Lighting Fixture for Electric Lamps, of which the following is a specification, reference being had to the accompanying drawing, forming a part thereof.

The figure is a perspective view of a lighting fixture for electric lamps showing my new design.

I claim:

The ornamental design for a lighting fixture for electric lamps, substantially as shown.

GUSTAVE W. BORKLAND.
